UNITED STATES PATENT OFFICE

CARROLL E. DODSON, OF KANSAS CITY, MISSOURI, ASSIGNOR TO L'ART MANUFACTURING COMPANY, OF KANSAS CITY, MISSOURI, A CORPORATION OF MISSOURI

CONTAINER OPENER

Application filed December 29, 1927. Serial No. 243,227.

My invention relates to containers and more particularly to paired members of a device having resilient means for latching them releasably in closed position, the principal object of the invention being to release the members from engagement, and incidental objects being to provide a member suitably supported by the device for moving the members apart and incidentally releasing the latch.

In accomplishing these and other objects of the invention, I have provided improved details of structure, the preferred forms of which are illustrated in the accompanying drawings, wherein:

Fig. 1 is a perspective view of a container in closed and latched position equipped with my container opener.

Fig. 2 is a detail perspective view of the opener.

Fig. 3 is a fragmentary view of the container including an elevation of the opener and supporting means.

Fig. 4 is a perspective view of the container showing the members in open position and illustrating the engagement of the opening device from inside the container.

Fig. 5 is a side view of the container illustrating the opening device in position after separating the members.

Fig. 6 is a vertical central section through the container, latch and opening device, illustrating the members in closed position.

Fig. 7 is a similar view illustrating the members in open position.

Referring in detail to the drawings:

1 and 2 designate frame elements adapted to be associated, and are illustrated as comprising a container and pivotally connected by a hinge 3, the element 1 being shown as the pan or body member of the container, and 2 as the top, cover or lid member. Means for engaging one element with the other are illustrated as a boss or rib-like outer edge 4 on one of the members, namely, the lid 2, and a latch 5 supported by the other member 1 adapted to engage the boss, the latch 5 being preferably curved and resilient and comprising a spring snap latch. The latch is supported by a latch member 6 preferably com-

prising an annulus 7 fitted into the body member and retained therein by the curved and indent rim 8 of the body member, the latch comprising an out-struck portion of the annulus.

Ordinarily, devices of this nature are opened by manually separating the latched edges and so disengaging the latch. I provide mechanical means for facilitating the separation of the engaged edges and comprising a yoke-like opener 9 having arms 10, and I further provide ears 11 preferably out-struck from the annulus 7 and formed into bearing portions on each side of the latch to receive a pivot pin 12 whereon the yoke-like opening element is pivotally mounted, the pin extending through suitable openings in the ears 11. The opening element is preferably provided with convex cam faces 13, which are adapted to bear against the rim of the cover upon pivoting of the opening element in the direction of the cover under pressure upon the face of a cross arm 14 of the opener to cause a wedging action against the cover upon the fulcrum of the body-supported pin.

In using a container equipped as described, the lid is brought down against the body portion in the usual manner so that the latch engages the boss of the lid. When the box is to be opened, the opening element is pivoted on its pin support and pressed against the lid, the cam faces sliding over the edge of the lid and forcing the members apart against the influence of the spring snap latch, the engaging edge of which is moved away from the boss. The opening element is provided preferably, therefore, on the body member with an arm on each side of the latch, both for efficient functioning to separate the members and also for guarding the latch against receiving or causing damage and for improving the appearance of the container.

What I claim and desire to secure by Letters Patent is:

1. In combination with a container comprising separable members and a spring snap latch, a cam element pivotally supported by one of the members and adapted for bearing against the other member to separate the members and disengage the latch.
